CLAIM

The ornamental design for a ferrule package, as shown and described.

DESCRIPTION

FIG. 1 is a side perspective view of a ferrule package;

FIG. 2 is a front side view thereof;

FIG. 3 is a back side view thereof;

FIG. 4 is a top view thereof; and,

FIG. 5 is a bottom view thereof.

The ferrule package is shown with a break in its length. The appearance of any portion of the article between the break lines forms no part of the claimed design. The broken lines in FIGS. 1, 2, 4 and 5 represent the claimed tear strip portion of the package.
